UNITED STATES PATENT OFFICE.

WILLIAM H. STOOPS, OF BOONTON, NEW JERSEY, ASSIGNOR TO JOSHUA S. SALMON, OF SAME PLACE.

SEALED LOCK FOR CANS.

SPECIFICATION forming part of Letters Patent No. 400,505, dated April 2, 1889.

Application filed September 10, 1888. Serial No. 285,037. (No model.)

To all whom it may concern:

Be it known that I, WILLIAM H. STOOPS, a citizen of the United States, residing at Boonton, in the county of Morris and State of New Jersey, have invented a new and useful Sealed Lock for a Milk or other Similar Can, of which the following is a specification.

My invention relates to that class of locks for milk-cans which are contained wholly within the can itself.

Hitherto the devices for the purpose of locking milk-cans have consisted of large springs requiring a number of subsidiary parts for the effective operation of the same.

The objects of my invention are, first, to provide a locking device without any springs and with the least number of subsidiary parts, thus enhancing its cheapness to the public; second, to provide a locking device that will offer no obstacle to the proper and easy cleansing of itself, the can, or of the cover; third, to provide a locking device so arranged that in the event of breakage of any of its parts the cover will be automatically unlocked, thus avoiding the necessity of damaging the can or its cover; fourth, to provide a simple mechanism that will prevent access to the contents of the can without detection, and also adulteration of the same while in transit. I attain these objects by means of the devices illustrated in the accompanying drawings, in which the same letters refer to like parts.

Figure 1 shows the mechanism in position in the cover of the can, showing the position of the device when locked. Fig. 2 is a detail of the tongue C, with its safety-hook D attached. Figs. 3 and 4 are modifications, and Fig. 5 is the grappling-hook.

I is the can.

J is the cover, in the center of the top of which a circular opening is made.

C is a tongue provided with a slight offset downward, and has pivoted to it a safety-hook, D. The tongue C is attached to the under side of the cover J, so as to project nearly, but not quite, across the opening made in the cover.

S S are two ears, which are attached to the inner side of the cylinder of the cover. They serve as points of support to the lever-arms A A.

A A are two lever-arms, so constructed that in their normal position the upper and lower ends of each lever is in the same vertical line, thus unlocking the cover and can.

55

B is a chain of such length that when down it permits the lever-arms A A to assume their normal position—viz., unlocked—and when drawn up over the tongue C throws the lever-arms under the shoulder of the can and holds them rigidly, as shown at A, Fig. 1—viz., locked. The safety-hook D prevents the chain from slipping off the tongue C.

H is a small hub, perforated laterally, resting on the upper surface of the cover. It passes downward through the tongue and serves the purpose of aiding to secure the tongue C in position, of holding the cap G, which serves to close the opening in the cover, and of providing for the sealing of the cap G by means of a thong, N, of leather or other suitable material. The cap G is pivoted to the upper surface of the cover, and when sealed prevents the inside mechanism from being operated or unlocked without detection. 75 The rivet g, on which the cover G is loosely pivoted, has a slanting or beveled head, which allows the cover to be raised to pass over the hub H.

The thong N may be provided with a suitable brand or device to prevent substitution without detection.

The operation of my improved lock is as follows: Assume the chain B to be down. The lever-arms A A will be in position unlocked, 85 as shown at A', Fig. 1. Place the cover of the can on in the usual manner. Then by means of a small hook, P, draw up the chain B till it rests across the tongue C and throw down the safety-hook D. The cover will be clamped 90 down to the can, Fig. 1. Close the cap G, which is provided with an opening to admit of the hub H passing upward through it, as shown in Fig. 2. Pass the thong N through the hub H and knot hard close to the hub and 95 cut off the end close to the knot. Should any one succeed in untying the knot, it would be found impossible, owing to its shortness, to retie it. To unlock, cut the thong N, open the cap G, and throw off the chain B. The 100 lever-arms A A will drop by gravity and the cover be unlocked. In like manner should

the chain B be broken the cover would be unlocked automatically. Thus the objects before enumerated are attained.

It will be obvious that the opening in the cover may be made so small as to be a mere slit, admitting of a link of the chain B, or a single link attached to said chain, being passed up through it, so as to project slightly above the surface of the cover, as shown in Fig. 3. A fine auxiliary wire could be passed through the link and then through the slit in the cover, and the cover then placed on the can. The chain B could be drawn up by means of the threading-wire till the link was above the surface and then held till the thong was passed through the link and knotted, as before described. The thong and the cover itself would be the resistance. The threading-wire could then be withdrawn. Thus the cap G, hub H, and the tongue C, with its safety-hook D, might be dispensed with, if convenient, and the objects before enumerated be effectively attained.

Instead of the chain and the tongue, the upper ends of the lever-arms A A may be elongated so as to extend upward into the opening in the cover, their ends being brought close together when the lower ends are thrown outward and the upper ends secured by a link or ring attached to one of the ends passed over the other, as shown in Fig. 4. The opening then would be closed by means of the cap G and thong N, as before described.

Having fully described my invention, what I desire to claim and secure by Letters Patent is—

1. The combination, with a can, of two or more levers pivoted to the inside of the cover, their lower ends being adapted to project under the shoulder of the can, and means for

drawing toward each other the upper ends of the levers and retaining them in that position, substantially as described.

2. The combination, with a can, of the levers A, pivoted to the inside of the cover and adapted to engage with the shoulder of the can, a chain, B, loosely uniting the ends of the levers, and means for putting and retaining a tension on the chain, substantially as described.

3. The combination, with a can, of two or more levers, A, pivoted to the inside of the cover and adapted to engage with the shoulder of the can, a chain, B, loosely uniting the levers, a tongue, C, fastened to the inside of the cover and adapted to receive the chain B, and a safety-catch for retaining the chain upon the tongue, substantially as described.

4. The combination, with a can, of a cover having an opening therein, two or more levers pivoted to the inside of the cover and adapted to engage with the shoulders of the can, a chain, B, loosely uniting the levers, a tongue, C, fastened to the inside of the cover adjacent to the opening and adapted to receive the chain B, a lid, G, for closing the opening in the cover, and means for sealing it when closed, substantially as and for the purpose set forth.

5. The combination, with a can, of the levers A, pivoted to the inside of the cover and adapted to engage with the shoulder of the can, a chain, B, loosely uniting the ends of the levers, means for putting and retaining a tension on the chain, and means for securing the chain from being tampered with without detection, substantially as described.

WILLIAM H. STOOPS.
